Primary Examiner — Cathron Brooks*Assistant Examiner* — Teddy Falloway(74) *Attorney, Agent, or Firm* — Christie, Parker & Hale, LLP(57) **CLAIM**

The ornamental design for dispenser and waste cabinet, as shown and described.

DESCRIPTION

FIG. 1 is a perspective view of our new dispenser and waste cabinet design;

FIG. 2 is a front view of our new dispenser and waste cabinet design;

FIG. 3 is a left side view of our new dispenser and waste cabinet design;

FIG. 4 is a right side view of our new dispenser and waste cabinet design;

FIG. 5 is a top view of our new dispenser and waste cabinet design; and,

FIG. 6 is a bottom view of our new dispenser and waste cabinet design.

The broken lines shown are included for the purpose of illustrating portions of the dispenser and waste cabinet that form no part of the claimed design.

1 Claim, 4 Drawing Sheets(56)
